US00D423037S

United States Patent [19]

Ohki et al.

[11] Patent Number: Des. 423,037

[45] Date of Patent: ** Apr. 18, 2000

[54] **ELECTRONIC VALUE PROCESSING DEVICE**

[75] Inventors: **Masayuki Ohki**, Kodaira; **Atsuhiko Urushihara**, Higashiyamato; **Koji Suso**, Kokubunji; **Jun Furuya**, Hachioji; **Takashi Matsubara**, Kodaira; **Yuhei Abe**, Hitachinaka, all of Japan

[73] Assignee: **Hitachi, Ltd.**, Tokyo, Japan

[**] Term: **14 Years**

[21] Appl. No.: **29/090,248**

[22] Filed: **Jul. 2, 1998**

[30] **Foreign Application Priority Data**

Feb. 27, 1998 [JP] Japan 10-5117

[51] **LOC (6) Cl.** **18-01**

[52] **U.S. Cl.** **D18/4**
